UNITED STATES PATENT OFFICE.

ALBERT A. CARY, OF NEW YORK, N. Y.

STEAM-GENERATOR.

1,109,041.

Specification of Letters Patent.

Application filed October 26, 1911. Serial No. 656,798.

To all whom it may concern:

Be it known that I, ALBERT A. CARY, a citizen of the United States, and a resident of New York, county of New York, and State of New York, have invented certain new and useful Improvements in Steam-Generators, of which the following is a specification.

This invention relates to certain new and useful improvements in methods and apparatus for generating steam, and more particularly to that of the water tube type.

One object of my invention is to provide an arrangement of the class described, which is extremely simple and efficient and yet much reduced in size, as compared with prior steam generators of the same capacity.

A further object of my invention is to provide a method and steam generator in which the steam generated shall always pass in the same direction as the water in the steam generating tubes, and in which all of the steam generating tubes are arranged substantially parallel so that the space occupied by the boiler is much reduced, and the boiler as a whole rendered more efficient.

A further object of my invention is to provide a boiler with one or more of the above advantages, and in which the water tubes are arranged in successive banks, and in which water is supplied to the lower end of each bank of tubes but passes successively downwardly from bank to bank.

A further object of my invention is to provide such an arrangement with one or more of the above advantages, in which the steam generated in the various banks of tubes is collected at the head of each bank or section and taken directly to the steam drum without being caused to pass through other banks of water tubes, or through intervening bodies of water.

A further object of my invention is to provide improved means for controlling the water supply to such generators, and an improved means for freeing the steam from water before the steam is passed to the steam drum.

Further objects, features and advantages will more clearly appear from the detailed description given below, taken in connection with the accompanying drawings which form a part of this specification.

Referring to the drawings, Figure 1 is a vertical section of a steam generator embodying my improvements in one form,

taken on the line I—I of Fig. 2, certain parts being shown somewhat diagrammatically for the sake of clearness. Fig. 2 is an elevation, the right hand portion being a section taken on the line II—II of Fig. 1, and the left hand portion being a front view of Fig. 1. Fig. 3 is a detailed front elevation showing the steam pipes connecting the various headers. Fig. 4 is a detail section taken on the line IV—IV of Fig. 3. Fig. 5 is a vertical section of a modified form of generator taken on the line V—V of Fig. 6. Fig. 6 is a vertical section taken on the line VI—VI of Fig. 5. Figs. 7 and 8 are vertical sections of still further modified form of generator. Fig. 9 is a detail section taken on the line IX—IX of Fig. 8.

Referring to Figs. 1, 2, 3 and 4, 1 represents the grate, 2 a steam drum, and 3, 4 and 5, water drums of a steam generator. The generator is provided with a series of banks of water tubes A, B, C, D, E and F. Each bank in this construction is provided with a double row of tubes 6 and 7. All of the tubes of the various banks are arranged substantially parallel and inclined upwardly toward the front of the generator, and the banks are arranged closely adjacent to one another, and successively below one another. The upper front ends of the tubes of each bank enter headers 8, 9, 10, 11, 12, and 13, respectively, while the lower ends of the tubes of each bank enter headers 14, 15, 16, 17, 18, and 19, respectively, thus forming a plurality of sections.

Arranged adjacent to the rear headers 14 to 19 inclusive is a series of chambers 20, 21, 22, 23, 24, 25 and 26. Leading from the water drum 5 is a water supply pipe 27 which enters the chamber 20. The pipe 28 connects the chamber 20 with the top rear header 14. The pipe 29 connects the front header 8 with the chamber 21. A pipe 30 connects the chamber 21 with the rear header 15. A pipe 31 connects the front header 9 with the chamber 22. A pipe 32 connects the chamber 22 with the rear header 16. A pipe 33 connects the front header 10 with the chamber 23. A pipe 34 connects the chamber 23 with the rear header 17. A pipe 35 connects the front header 11 with the chamber 24. A pipe 36 connects the chamber 24 with the rear header 18. A pipe 37 connects the front header 12 with the chamber 25. A pipe 38 connects the chamber 25 with the rear header 19.

19. A pipe 39 connects the front header 13 with the chamber 26. A pipe 40 connects the chamber 26 with the rear header 19. A pipe 41 connects the chamber 20 with the steam drum 2. A pipe 42 connects the steam drum 2 with the water drums 3, 4, and 5, and also with the chamber 20, in order to equalize the pressure throughout the system. The chambers 20 to 26 inclusive, are connected to one another by escape pipes 43' so that any air or vapor which may collect in any of these chambers may readily pass upward through the various chambers and the pipes 43' and 42 to the steam drum 2, thus supplying water free from air or vapor to headers 14, 15, &c. The various pipes 28 to 38 inclusive, are arranged at one side of the banks of steam generating tubes A to F, and are preferably built in the brick-work of the generator, so that they are substantially outside of the main heat zone.

The various front headers 8 to 13 are connected together by means of steam pipes 43 bent U-shaped so that the steam which collects in the front headers may pass rapidly upward from header to header until it reaches the top front header 8 whence it is connected to the steam drum 2 by means of pipes 44. Pipe 42' supplies the drums 3, 4, and 5 with water.

The operation of the parts so far described will be clearly understood from the following. Water enters the chamber 20 from the water drum 5, thence it passes downwardly through pipe 28 and floods the upper rear header 14, thereby flooding the tubes 6 and 7 of the bank A. Water flowing out of the top ends of these tubes through pipes 29 enters the chamber 21 whence it flows downwardly through pipe 30 into the rear header 15 of the next succeeding bank below, flooding the tubes of the section or bank B. The water in these tubes flows upwardly into the front header 9 whence it passes through pipes 31 to the chamber 22, thence downwardly to the rear header 16, flooding the bank C, then into the upper header 10 through pipes 33 into the chamber 23, thence downwardly through pipe 34 into the chamber 17, flooding the bank D, then from the front header 11 through tubes 35 into chamber 24, thence downwardly into the rear header 18 flooding the bank E, and from header 12 through pipes 37 into chamber 25, thence downwardly through pipes 38 into the lower rear header 19, flooding the lower bank of tubes F. Any overflow from these tubes into the front header 13 may pass through pipes 39 into chamber 26 which is connected with the rear header 19 by pipe 40. It will thus be seen that the course of the water through the boiler is upwardly in all of the tubes 6 and 7 of each bank, but is downwardly from bank to bank so that all of the steam generated in the

banks of tubes A to F passes upwardly therein in the same direction in which the water passes through them, thereby facilitating the movement of the steam to the front headers 8 to 13. In the front headers 70 8 to 13 the water is separated from the steam, the water passing through the pipes 29 etc., the steam passing upwardly through the pipes 43 and 44 to the steam drum 2. Thus a progressive heating of the water is 75 provided in the generator itself, the rear headers being purely water headers, while the front headers are steam headers and in which practically all of the steam is collected. A pipe 45 connects the three water 80 drums 3 and 4 and 5 together so as to equalize the pressure and water level therein. Some water will be condensed in the steam drum 2 and when its level rises above the top of the pipe 41, water will flow 85 down through pipe 41 to chamber 20, to act as feed water for the generator. To take off any air which might collect in pipe 27 a pet cock 27' is provided.

Referring more particularly to Figs. 3 90 and 4, the various front headers such as 9 and 10 are provided with hand hole openings 46 covered by plates 47 held in position by means of spiders 48 and bolts 49. The hand hole openings are arranged elliptical 95 in shape so as to permit the ready entrance of the plates 47, and are also arranged of proper size to permit the withdrawal of the tubes 7 of the various banks. Opposite the tubes 6 of each bank are arranged openings 100 through which the tubes 6 of each bank may be withdrawn. In these openings at 50 are placed spring rings 51 against which are seated the beveled ends of the connecting U pipes 43. The U-bends 43 connect the 105 front headers with one another as is clearly shown in Figs. 1 to 4. The U-bends are thoroughly forced into and held in place by means of clamps 52 provided with hooks 53 engaging under pins 54. The pins 54 extend 110 between uprights 55, integral with or secured to the front sides of the front headers. The U-bent pipes 43 are provided with bosses 55 which are adapted to be engaged by screws 56 passing through the clamps 52, 115 so that by operating the screws 56 the U bent pipes may be thoroughly forced into place to form a steam tight joint and properly connect the front headers so as to form a direct passage of the steam from one 120 header to another upwardly to the steam drum.

In order to properly free the steam from water as it leaves the upper ends of the tubes 6 and 7, and prevent the steam from 125 carrying water with it up through the connecting pipes 43, I provide baffles 57. The baffles 57 are arranged opposite the ends of the U-bent pipes 53. These baffles are hollow and tubular in shape and provided with 130

flanges at 58, which are seated in the seats of the openings 50. The ends of the baffles 57 opposite the pipes 43 are closed as by partitions 59, and the tops of the baffle members are cut away as at 60. The baffle members are provided with openings 61 in their bottom portions, as clearly shown in Fig. 4. It will be understood that the outer ends of the tubular members 57 opposite the partition 59 are open and lead directly into the pipes 43.

From the above it will be clear that as the steam and water rush out of the upper pipes 6 into the front headers, the steam and water will strike the partition 59, the water being caused to drop downwardly while the steam passes over the top of the partition 59 through the cutaway part 60 and into the baffle member itself. The steam then has free passage upwardly through the pipes 43 to the steam drum. Any water which may collect in the baffle member 57 is drained out through the openings 61.

In order to provide suitable and automatic means for regulating the supply of water to the generator, I provide a pipe 62 extending into the chamber 26, thence upwardly through the pipes 43 and into a condenser at 63. The condenser 63 is provided with a plurality of passes as 64, 64 through which steam from the pipe 62 is caused to pass. From the lower pass 64 of the condenser 63 a pipe 65 leads into the water drum 5, and thence into a chamber 66 situated in the water drum 5. The chamber 66 in the present instance is formed of a relatively large pipe bent U-shape, and the supply pipe 27 extends upwardly through the bottom of the drum 5 and into the chamber 66. For operating the condenser cold water pipes 67 are provided therein and supplied with cold water from the supply pipe 68. After passing through the condenser the cold water is delivered to the drum 5 by means of a pipe 69 where it may be used as feed water. The lower end of the pipe 62 in the chamber 26 is situated at the level at which it is desired to maintain the water in the front header 13, that is, at a level sufficient to flood the lower bank of pipes F.

Should the water in the chamber 26 be lowered below the lower end of the pipe 62, then steam which collects in the chamber 26 will pass upwardly in the pipe 62 to the condenser 63. The steam being condensed in the condenser 63 produces a suction or partial vacuum in the chamber 66, thereby causing the level of the water in chamber 66 to be raised relatively to the level of the water outside of the chamber 66 and in the drum 5. This raises the level of water in the chamber 26 above the top of the supply pipe 27, causing water to be delivered through the pipe 27 to the chamber 20 from water drum 5. In order that the desired vacuum may be

properly produced in the chamber 66, and not be too quickly reduced by the admission of too much steam from the lower end of the pipe 62, there is provided in the pipe 62 a plate 67 provided with one or more small perforations therein. Thus the passage of the steam through the pipe 62 is much retarded by the perforated plate 67 so as to allow the formation of a sufficient reduction of pressure in the chamber 66 to cause water to be sucked upwardly therein in the openings in the bottom of the chamber 66 from the drum 5. This action causes water to be supplied to the chamber 20 from which it is in turn supplied to the various banks of tubes as already explained, until it reaches the lower bank of tubes F where it will raise the level of the water therein and in the chamber 26 until it reaches and closes the lower end of the pipe 62 whereby further admission of steam to the pipe 62 is prevented, thereby causing the action of the condenser 63 to cease, whereupon the level of the water in the chamber 66 will not be further increased above the top of the pipe 27, and further supply of water to the generator is cut off.

By the means above described the supply of water to the generator is automatically controlled so as to maintain the water level in the chamber 26 substantially at the lower end of the pipe 62, and thereby cause the lower bank of tubes F to be continually flooded with water under a suitable head. It will be understood of course that if the lower bank of tubes F is sufficiently supplied with water, the other banks above will be sufficiently supplied with water, since water can not be supplied to the bank F until all of the other banks are properly filled.

Referring to the modification shown in Figs. 5 and 6, the generator there shown is provided with the usual grate 70 and with a series of banks of tubes G, H, I, J, K and L. The tubes of these banks are all inclined and substantially parallel to each other and arranged closely adjacent to one another as in Fig. 1. Front headers are provided for each bank as at 71, 72, 73, 74, 75 and 76, while corresponding rear headers are located at 77, 78, 79, 80, 81 and 82. In order to conduct the water emptied into any front header to the rear header of the bank below, pipes 83, 84, 85, 86, 87 and 88 are provided, the pipe 83 leading from the front header 71 to the second rear header 78, the pipe 84 leading from the front header 72 to the third rear header 79, the pipe 85 leading from the front header 73 to the fourth rear header 80, the pipe 86 leading from the front header 74 to the fifth rear header 81, the pipe 87 leading from the front header 75 to the lower rear header 82, and the pipe 88 leading from the front header 76 to the lower rear header 82. A

supply pipe 89 leads from the steam and water drums 90 to the upper rear header 77, and water may be supplied through said pipe to properly supply the generator in any well known manner. It will be understood that the pipes 83 to 88 inclusive, are arranged at the sides of the various banks of steam generating tubes G to L inclusive, and preferably in the side walls or brickwork of the generator or so that they are substantially outside of the main heat zone. The front headers are each provided with pipes 91 which connect each front header with the header above it, and extend upwardly therein sufficiently to allow a proper depth of water to be maintained therein without it flowing to the header below. It will therefore be clear that the steam which is delivered into the front headers from the various banks of tubes G to L inclusive, will readily pass upward through the pipes 91 into the upper header 71, and thence by pipe 92 into the steam space of the drum 90. In case the water in any of the front headers should rise higher than desired, there are provided a series of pipes 93 connecting the front headers with one another, having their lower ends sealed in the water in the header below. In case the water in any front header rises above the top of these pipes it will pass therethrough to the header below, thus supplying water to any bank below which needs the same. The general operation of this modification, as will be readily understood, is substantially the same as the operation of the generator shown in Fig. 1.

Referring to Fig. 7 the modification there shown is provided with the usual grate 100, and with a series of banks of water tubes M, N, O, P and Q. These tubes are all inclined upwardly toward the front of the generator, and are provided respectively with front headers 101, 102, 103, 104 and 105, and with rear headers 106, 107, 108, 109 and 110. The top front header 101 is connected to the rear header of the bank below by the pipes 111, which is at one side of the steam generating tubes and preferably in the brickwork of the generator. The front header 102 is connected with the rear header of the bank below by pipe 112. The front header 103 is connected with the header of the bank below by pipe 113, and the header 104 is connected with the lower rear header by pipe 114. Connected with the lowest rear header 110 by passage 115, is a chamber 116. It will therefore be seen that by the arrangement of the pipes described the water supplying the generator passes successively downward from bank to bank through the pipes 111 to 114, but that all of the steam generating tubes of the banks M to Q inclusive are inclined upwardly in the same direction so that the steam therein

passes upwardly in the same direction as the water, whereby it is more readily freed from the steam generating tubes. Each rear header is provided with an upward extension 117 extending upwardly into the header above, but sealed with respect thereto. Each of the upward extensions 117 is provided with a connecting pipe 118 which extends upwardly into the extension 117 of the header above. This arrangement allows of the level of the water in the various headers rising up to or above the lower ends of the tubes of the bank above, and also provides a continuous passage to permit the escape of any air or vapor that may collect in the rear headers so that this air or vapor may pass upwardly through the various pipes 118 to the extension 117 of the top rear header whence it may pass by means of pipe 119 to the steam space of the steam and water drum 120. Thus the water is supplied to the lower ends of the steam tubes free from air or vapor. A pipe 121 connects the steam space of the drum 120 with the rear header 106 so that any steam or gas collected therein may be passed to the drum 120. For the purpose of collecting the steam delivered to the front headers, the front headers are provided with pipes 122 connecting each header with the header above. These pipes extend upwardly above the water level of the header above, and slightly below the water level of the header into which they extend below. It will therefore be seen that as steam collects in any of the front headers it at first has no means of escape therefrom, but as the steam collects it causes the pressure in the front headers to slightly rise, thereby depressing the water level therein until the water level is below the lower ends of the pipes 122, whereupon direct and free passage is afforded the steam through the pipes 122 to the header above from which it passes in the same manner to the next header above, and so on to the top header 101, where, in a similar manner, it passes into the steam space of the drum 120 by the pipe 123.

In order to properly regulate the supply of water to the generator, the supply pipe 124 leads from near the bottom of the steam and water drum 120 to a double seated valve 125. From the valve 125 the water is supplied through pipe 126 to the upper rear header 106. From the upper header 106 water is supplied to the remaining rear headers and banks of tubes in the same manner as described with regard to the modifications shown in the other figures. For operating the valve 125 the same is provided with a stem 127 which may be moved upwardly against the action of the spring 128 in order to supply water from the drum 120 to the header 106. Pivotaly connected with the spindle 127 is a lever 128 which is piv-

oted to the chamber 116 at 129. Pivottally connected to the discharge end of the lever is a float 130 floating in the water in the chamber 116. It will be clear that if the 5 level of the water in chamber 116 drops below a predetermined point, the weight of the float 130 will cause the valve to be opened against the action of the spring 128, thereby causing water to be supplied to header 106. 10 The level of the water in the chamber 116 is designed to be such as to properly flood the lower bank of tubes Q in order to keep them at all times as full of water as possible. As soon as the level of the water in chamber 15 116 rises sufficiently, or to the predetermined point as desired, the float 130 is raised likewise so as to close the valve 125 and shut off the supply of water.

In respect to all three forms of generator 20 it will therefore be seen that the water circulation is by one continuous flow through all of the water tubes, first through the upper bank, then through the bank next below, and so on down to the bottom bank or 25 row of tubes. By this the water is gradually heated until it reaches the bottom bank of tubes where the temperature is greatest, and it is rapidly converted into steam. Since the connecting pipes such as 29, &c., in Fig. 30 1, all pass at one side of the banks of steam generating tubes, the generation of steam therein is practically prevented so that practically no steam is generated therein which would retard or hinder the solid body of 35 water from flowing therethrough to any material extent. It will of course be understood that a very small quantity of steam may be carried along with the water in these side tubes, and an immaterial amount of 40 steam might be generated therein. But the generation of steam therein is cut down to a very small amount so as not to interfere in any way with their capacity for conducting the water, and practically all the steam 45 generated in the generator is rapidly taken off at the upper end of each bank of tubes and directly conducted to the steam drum 2 without having to pass through any part but the upper ends of each of the steam generating tubes in which it is generated. By 50 inclining the steam generating tubes as shown the flow of water therein is always upward toward the front header where the steam is taken off. Thus the steam in 55 escaping passes along with the water and tends to aid in the movement of the water, and the movement of the water tends to aid in the movement of the steam to get it out of the water tubes as soon as possible in order 60 that they may be refilled with water as soon as possible. By thus keeping the steam generating tubes, and especially the lower bank of tubes, rapidly filled with water, the efficiency thereof is very considerably increased.

In some classes of boilers the front header is not made of horizontal sections, and is substantially filled with water to its top. In such case the steam generated at the lower tubes has to pass through all this head 70 of water, and water and steam together are discharged into the overhead drum, which is disadvantageous. In my improved boiler, however, the steam generated in the lower bank of tubes has a free path directly to the 75 steam drum and flows alone into that drum.

It has been pointed out that the water fed through the generator is progressively heated from the time it enters the boiling until it is evaporated into steam. As will 80 readily appear, this is done by providing what is like a continuous coil of pipes, the water passing as in Fig. 1 through the bank A and return tubes 29 and 30 forming one coil, then through bank B and return tubes 85 31 and 32 forming the next coil, and so on. The legs of each coil which are subjected to the furnace gases all extend upwardly to the front header where the steam is taken off from each leg separately from its highest 90 level. The downward leg, that is, one composed of the return pipes such as 29 and 30, passes outside of the boiler proper so that it is not subjected to the furnace gases, and little or no steam is generated therein. The 95 steam does not have to pass through the return pipes such as 29 and 30 and 31, &c., in order to get to the steam drum, where, if it did, it would collect on the top surface of the pipes 29, 31, &c., and form pockets 100 which would not be readily filled with water, thereby decreasing the efficiency of the boiler. By quickly and readily removing the steam from the banks of steam generating tubes, the same are quickly refilled, 105 thereby keeping all of them just as full of water as is possible all of the time so that the greatest amount of heat may be taken up so as to cause the greatest transmissive efficiency possible. The steam in no part 110 of the boiler has to pass in a direction contrary to the movement of the water but always with it, and steam generated in the lower banks of tubes cannot be diverted from its upward passage to the steam drum 115 120 so as to flow downward through the upper banks of tubes toward the rear headers, as occurs in certain other types of water tube boilers. Furthermore by providing the water circulation so that it passes downwardly from bank to bank and is progressively heated, the colder water is on top, and since the colder water is much more dense than the heated water below it causes a greater head 125 to be produced, thereby making the circulation more active and efficient to more rapidly refill the banks below as may be necessary. Also by placing the return pipes 29, 30, 31, 32, &c., at one side or in the brickwork of the generator, the steam generating banks 130

may be arranged closely adjacent to one another so as not only to minimize the size of the boiler as a whole, but to get the greatest amount of energy from the hot gases resulting from the fuel burned, thereby getting the greatest efficiency out of the boiler.

With regard to Fig. 1 any steam air or gas which might collect in the pipes 29, 31, &c., is carried to the chambers 21, 22, &c., where 13 it is allowed to escape freely by means of pipes 43' to the steam drum 2.

A further advantage in having the coldest water in the top banks of the boiler, and the hottest water in the lower banks, is that as 15 the heated gases of combustion pass upwardly they are of necessity more or less cooled so that in abstracting further heat energy therefrom the colder the pipes are at the top the greater amount of heat energy 20 will be taken from these gases. This of course increases the efficiency of the boiler and at the same time allows the boiler to have all the other advantages pointed out.

A further advantage of the progressive 25 circulation and heating is that in all such boilers there is a certain amount of scale which is thrown down in the tubes of the boiler and in many forms this is precipitated in the lower bank of tubes where be- 30 cause of the excessive heat it is baked hard upon them, but in the form of boiler which I have described any scale which enters the generator would be first thrown down in the upper banks of tubes, and before it reaches 35 the lower bank of tubes. Being thrown down in the upper bank of tubes it does not bake hard upon them because they are not so highly heated and it may therefore be more easily removed. Since this scale and 40 these impurities are not thrown down in the lower banks of tubes nearest the fire, it leaves the lower tubes always free whereby they are able to generate steam at the position of greatest efficiency and the heat-con- 45 ducting power thereof is not diminished. This is of very considerable importance since the greatest heat transmission takes place at the lower tubes, and it is important that these be kept clean in order that the heat 50 transmission thereof may not be diminished. The efficiency of the boiler is not so ma- terially decreased because of the deposit of softer scale in the upper tubes as the relative heat transmission of the upper tubes is 55 comparatively smaller. The water therefore arrives at the lower banks of tubes pure and very much heated. Each section discharges its steam as rapidly as it is generated, and gets rid of any excess of water with des- 60 patch above the quantity needed for the section to perform its perfect function.

It will further appear that the pipes 43 connecting the various front headers connect only with the top parts of said headers 65 so that only steam gets into them, and they

are not blocked in any way by water but are always kept free for the passage of steam to the steam drum 2.

Referring to Fig. 1 the cold feed water, aside from the quantity introduced in the 70 condenser 63, is introduced into the second drum 3, which being placed over the heating chamber of the boiler, absorbs a certain amount of heat. The water then flows to the drum 4 where it continues to absorb more 75 heat, and thence to the drum 5 where, after absorbing more heat, it is supplied through the pipe 27 to the rear header 20. By extending the chamber 66 as nearly as possible to the bottom of the water drum 5, it will 80 be seen that practically the entire water contents of the overhead water drums is available to supply the water tubes below. Thus if the attendant neglects to keep the water drums at any predetermined fullness, or 85 should the water feeding apparatus be stopped due to carelessness, or due to accident, substantially the entire remaining contents of the water drums will be available to supply the boiler tubes with water. Thus 90 no exact predetermined water level in the overhead drums is made necessary. The pressure-operated device for regulating the flow of water to the water tubes of the generator, shown in Figs. 1 and 2, entirely 95 eliminates all valves and other parts me- chanically moved. The perforated plate 67 may be provided with several small perforations so that there is no substantial danger of them all becoming stopped at the same 100 time by foreign particles or the like. If de- sired, an ordinary gate, globe or plug valve, could be substituted for the plate 67, or a ball, flap or mushroom check valve could be similarly substituted, which would close au- 105 tomatically when a certain vacuum pres- sure was reached, admitting successive amounts of steam afterward as the intensity of the vacuum diminished, all of which de- vices are known in places desiring similar 110 service.

The baffle 57, shown in Figs 3 and 4, is es- 115 pecially efficient in that it can be very easily removed. Upon the removal of the U-bent pipes 43 the baffles 57 are easily slipped out, thus leaving the openings free for the re- 120 moval of the steam generating tubes 6 or for cleaning as desired. If desired the baffle 57 may be made integral with the pipe 43, therefore making it unnecessary to fit the baffle into the headers 7. The inclusion of the spring packing ring 51 prevents any leakage of steam and water around the seats of the pipes 43.

From the above it will be clear that I have 125 provided an exceptionally efficient steam generator of simple construction in which the water is progressively heated and caused to pass progressively downward from bank to bank of steam generating tubes, but in 130

which the steam always passes in the same direction with the water in the steam generating tubes, and in which the steam is taken off at the upper ends of each bank of tubes 5 and allowed to pass directly to the steam drum, whereby the water circulation is rendered most efficient, and the water arrives at the bottom banks of tubes in a most heated and efficient condition for the rapid generation of steam. Furthermore, by passing the return pipes 29 to 31, &c., outside of the banks of steam generating tubes, and substantially outside of the main heat zone, the steam generating tubes 6 and 7 may be 10 placed closely adjacent to one another and in staggered relation so as to absorb the greatest amount of heat from the hot gases. Furthermore, in placing the return pipes 29, 31, &c., outside as described, no substantial amount of steam is generated therein, so 15 that the water is given a most free circulation. By the construction of the boiler noted the generator may be pushed or forced very much above its rated capacity and in a 20 most efficient manner.

In Fig. 8 I have illustrated a modified form which embodies some of the novel features of my invention but which is far inferior to the construction illustrated in Fig. 30 1, etc.

In the modification shown in Fig. 8, 130 represents a steam and water drum with a supply water pipe 131, and steam outlet 132. As in the other figures this construction is 35 provided with front steam headers 133, 134, 135, 136 and 137, and with rear water headers 138, 139, 140, 141 and 142. Extending downwardly from the front to the rear headers are banks of steam generating tubes 40 R, S, T, U and V. Feed water is fed from drum 130 to lower rear header 142 by means of pipe 143. The water then flows through the section of steam generating tubes V and that which is not transformed into steam is 45 poured into the front header 137, whence it is carried to the next rear header 141 by side pipes 144. Where the pipe 144 enters the header 141 it is provided with an elbow 145, one end 147, connecting with the pipe 144 and the other end 148 leading to the 50 header 141. This elbow also has leading from its top a pipe 146 which extends upwardly and into the steam space of the steam drum 130. The bottom of the elbow is 55 struck up as at 149 in order to form a sort of baffle which aids in separating any entrained gases from the water, causes the gases to be directed upwardly into the pipe 146 whence they are carried to the steam 60 drum, while the water drops back and flows into the rear header 141 through the end 148 of the elbow. Water from the rear header 141 then flows upwardly through the steam generating pipes U into the upper header 65 136 from which it flows through side pipe

150 to the next rear header 140. The water is then carried progressively upward through the steam generating tubes T, S and R, and the side pipes 151 and 152. The water is caused to flow upwardly in the 70 path described by means of the head of water in the feed pipe 143 and drum 130. Any entrained gases passing through the pipes 144, 150, 151 and 152 are carried off by the pipes 146, 153, 154 and 155 respectively. Where 150, 151 and 152, are connected to the pipes 153, 154 and 155 and the headers 140, 139 and 138, they are provided with elbows similar to 145. Any steam or gas which might collect in the rear header 80 142 is carried to the steam drum 130 by means of a pipe 156 leading from the top of the header. For the same purpose pipes 157, 158, 159 and 160 lead from the top of the headers 141, 140, 139 and 138 and connect with pipes 146, 153, 154 and 155 so 85 that any steam or gas which might collect in any of the rear headers will be properly conducted to the steam drum.

In order to conduct the steam collected 90 in the front steam headers 133 to 137 to the steam drum, pipes 161, 162, 163, 164 and 165 are provided connecting the steam drum with the header 133 and each front header with the header below. The lower ends of 95 these pipes are beveled off as at 166 and normally the water level in these headers is at the lower ends of these pipes. The steam generated in the section V being conveyed to the header 137 causes the pressure therein to increase so that the water level therein is depressed until the lower end of the pipe 165 is unsealed when the steam will pass 100 upwardly to the steam space in header 136. Here the same action will be repeated and so on up through the front headers until 105 the steam reaches the steam space in the drum 130. It will be noted that in this modification the water is fed upwardly through the generator so that this construction does not have the great practical advantage of the downward feed shown in the other figures. However it has considerable 110 advantages over some prior structures and might be found desirable in some cases.

Although I have described my improvements in great detail and with respect to certain particular forms, nevertheless many changes and modifications may be made therein without departing from the spirit and scope of my invention, and I therefore do not desire to be limited to any of the details shown and described except as clearly specified hereinafter in the appended claims.

Having thus fully and clearly described my improvements, what I claim as new and desire to secure by Letters Patent, is:

1. In a steam generator, a plurality of steam generating tubes, all inclined in the same direction, a header for each end of 130

each tube, means for taking off steam from the headers at the upper ends of said tubes, and means for conducting water from each of said last mentioned headers to the opposite header of the next succeeding tube below.

2. In a steam generator, a plurality of banks of inclined steam generating water tubes, front and rear headers for said banks, 10 said tubes being substantially all inclined in the same direction and means for admitting water to the lower end of each tube and causing the water to pass progressively downwardly through the successive banks 15 of tubes.

3. In a steam generator, a plurality of banks of inclined steam generating water tubes, front and rear headers for said banks of tubes, and means for conducting water 20 from the front header of one bank of tubes to the rear header of the bank below, said means being situated outside of the main heat zone whereby steam is not materially generated in said means.

4. In a steam generator, a plurality of inclined water tubes, and means for conducting water from the upper end of one tube to the lower end of the tube below, said means being situated outside of the main 30 heat zone whereby no material amount of steam is generated in said means.

5. In a steam generator a plurality of banks of inclined water tubes, the tubes of each lying substantially parallel to one another and extending in substantially a common plane, whereby the space occupied by the tubes is reduced, and means for conducting the water from the upper ends of each bank of tubes to the lower ends of the 40 next succeeding bank of tubes below.

6. A water tube steam generator having sets of steam generating water tubes, means for causing water to pass successively through the tubes from set to set and downward until it reaches the bottom set, and means for automatically maintaining a predetermined water level in connection with the supply end of the lower tubes.

7. In a steam generator a plurality of inclined water tubes, the upper end of one tube being above the lower end of the next succeeding tube above, and means for conducting the water from the upper end of each tube to the lower end of the next succeeding tube below.

8. In a steam generator the combination of front and rear headers, a plurality of banks of water tubes extending upwardly from the rear to the front headers, said 60 banks lying closely adjacent to one another, and means for conducting the water from the upper ends of each bank of tubes to the lower ends of the next succeeding bank of tubes below.

9. In a steam generator the combination

of front and rear headers, a plurality of water tubes, all of said tubes being inclined in the same direction whereby said tubes may be placed closely adjacent one another, and means for conducting the water from 70 the upper end of one tube to the lower end of a tube below.

10. In a steam generator the combination of front and rear headers, a plurality of banks of water tubes, all of said tubes being 75 inclined in the same direction whereby said banks may be placed closely adjacent to one another, and means for conducting the water from the upper ends of one bank of tubes to the lower ends of a bank of tubes 80 below, said means embracing water conducting means lying outside the main heat zone, whereby generation of steam therein is substantially prevented.

11. In a steam generator a plurality of 85 inclined water tubes, the upper end of one tube being above the lower end of the next succeeding tube above, and means for conducting the water from the upper end of each tube to the lower end of the next succeeding tube below, said means embracing water conducting means lying outside the main heat zone whereby generation of steam 90 therein is substantially prevented.

12. In a steam generator a plurality of 95 banks of water tubes, front and rear headers therefor, said tubes extending upwardly from one header to the other and lying in substantially parallel planes whereby the space occupied by the tubes is reduced, and 100 means for conducting the water from the upper ends of each bank of tubes to the lower ends of the next succeeding bank of tubes below, said means embracing water conducting means lying outside the main 105 heat zone.

13. In a steam generator a plurality of inclined water tubes, lying substantially parallel to one another, whereby the space occupied by the tubes is reduced, and means 110 for conducting water from the upper end of each tube to the lower end of the next succeeding tube below, said means embracing water conducting means lying outside the main heat zone whereby generation of steam 115 therein is substantially prevented.

14. A water tube steam generator having all its steam generating tubes inclined and fed with water at their lower ends whereby the water passes upwardly in said tubes 120 with the steam generated, said tubes being arranged in banks and means passing at one side of said steam generating tubes for conducting water from the upper ends of one bank of tubes to the lower end of the bank 125 of tubes below.

15. A steam generator having a plurality of banks of steam generating water tubes lying substantially parallel to one another, and means for conducting water from the 130

upper ends of the tubes of each bank to the lower ends of the tubes of the bank below, the lower ends of the tubes of one bank being below the upper ends of the tubes of 5 the next succeeding bank below.

16. A steam generator having a plurality of inclined water tubes lying in banks, front and rear headers for said banks, the rear header of each bank lying lower than the 10 front header of the same bank and connecting means whereby the water flows upwardly in each tube, but downwardly from bank to bank.

17. A water tube steam generator having 15 steam generating water tubes inclined upwardly in the same direction, and means for supplying water to the lower ends of said tubes and causing it to pass successively downwardly through said tubes to the bottom tubes of the generator.

18. A water tube steam generator having 20 a series of steam generating water tubes inclined upwardly and arranged in banks closely adjacent one another, a front and rear header for each bank, and conducting pipes for conducting water from the upper header of each bank to the lower header of the bank below.

19. A water tube steam generator having 25 a series of steam generating water tubes inclined upwardly and arranged in banks, closely adjacent one another, a front and rear header for each bank, and conducting pipes for conducting water from the upper header of each bank to the lower header of the bank below, said pipes being outside the main heat zone of the generator whereby the generation of steam is substantially eliminated therein.

20. A water tube steam generator having 30 a series of steam generating inclined water tubes, front upper headers for the tubes, rear lower headers for each bank, a plurality of chambers, one corresponding to each 35 rear header, means for conducting water from each chamber to its corresponding rear header, and means for conducting water from each front header to the chamber corresponding to the rear header of the bank below.

21. A water tube steam generator having 35 a series of steam generating inclined water tubes arranged in banks, a front upper header for each bank, a rear lower header for each bank, a plurality of chambers, one corresponding to each rear header, means 40 for conducting water from each chamber to its corresponding rear header, and means for conducting water from each front header to the chamber corresponding to the rear header of the bank below, and means for taking off steam which may collect in said chambers.

22. In a steam generator a plurality of 45 banks of water tubes, front and rear headers

therefor, said tubes extending upwardly from one header to the other and lying in substantially parallel planes whereby the space occupied by the tubes is reduced, and means for conducting the water from the 50 upper ends of each bank of tubes to the lower ends of the next succeeding bank of tubes below, and means for collecting steam from the headers at the upper ends of said tubes.

23. In a steam generator the combination 55 of front and rear headers, a plurality of water tubes extending upwardly from the rear to the front headers, said tubes lying closely adjacent one another, and means for conducting the water from the upper end of 60 a tube to the lower end of the next succeeding tube below, a steam drum, and means for conducting steam directly from each front header to the steam drum.

24. In a steam generator a plurality of 65 banks of inclined water tubes, the upper ends of one bank of tubes being above the lower ends of the next succeeding bank of tubes above, and means for conducting the water from the upper ends of each bank of 70 tubes to the lower ends of the next succeeding bank of tubes below, said means embracing water conducting means lying outside the main heat zone whereby steam will not be materially generated therein, a steam 75 drum, and means for conducting steam directly from the upper end of each tube to the steam drum.

25. A water tube steam generator having 80 a series of steam generating inclined water tubes arranged in banks, a front upper header for each bank, a rear lower header for each bank, a plurality of chambers, one corresponding to each rear header, means 85 for conducting water from each chamber to its corresponding rear header and means for conducting water from each front header to the chamber corresponding to the rear header of the bank below, a steam drum, means for conducting steam from each 90 front header directly to the steam drum, and means for conducting steam which may collect in said chambers directly to the steam drum.

26. A water tube steam generator having 95 a series of steam generating inclined water tubes arranged in banks, a front upper header for each bank, a rear lower header for each bank, said tubes all extending substantially parallel to one another and said 100 banks lying closely adjacent one another, a steam drum, means conducting the steam from each front header directly to the steam drum without passes through said tubes, and means for conducting water from each 105 front header to the rear header of the next lower bank of tubes, said last mentioned means passing at one side of said banks of tubes and lying substantially without the main heat zone of the generator whereby 110

the generation of steam in said last mentioned means is substantially eliminated.

27. In a steam generator a plurality of banks of water tubes, front and rear headers therefor, said tubes extending upwardly from one header to the other and lying in substantially parallel planes whereby the space occupied by the tubes is reduced, and means for conducting the water from the upper ends of each bank of tubes to the lower ends of the next succeeding bank of tubes below, steam conducting pipes for connecting each front header with the front header below and baffles in front of the ends of said pipes.

28. In a steam generator a plurality of banks of water tubes, front and rear headers therefor, said tubes extending upwardly from one header to the other and lying in substantially parallel planes whereby the space occupied by the tubes is reduced, and means for conducting the water from the upper ends of each bank of tubes to the lower ends of the next succeeding bank of tubes below, steam conducting pipes for connecting each front header with the front header below and baffles in front of the ends of said pipes, each baffle comprising a tubular shaped member closed at its end farthest from said pipes and cut away on its top side and provided with an aperture in its bottom.

29. A steam generator having a series of steam collecting headers, steam conducting pipes for connecting the front of each header with the front of the header below and baffles in front of the ends of said pipes, each baffle comprising a tubular shaped member closed at its end farthest from said pipes and cut away on its top side and provided with an aperture in its bottom.

30. A steam baffle for steam generators comprising a tubular shaped member closed at one end and open at the other and cut away on its top side and provided with an aperture in its bottom.

31. The combination of a plurality of headers for steam generators, said headers being arranged one above another, steam conducting pipes for connecting the front of each header with the front of the header below, said headers being provided with openings for the reception of the ends of said pipes, and removable baffles opposite the ends of said pipes, each baffle comprising a hollow shaped member closed at its end farthest from said pipes and having a flange fitting within the header opening and the baffle being cut away on its top side and provided with an aperture in its bottom.

32. A water tube steam generator having substantially all of its steam generating water tubes inclined in the same direction and means for causing the water to pass suc-

cessively downwardly from tube to tube 65 until it reaches the bottom tubes.

33. A water tube steam generator having sets of steam generating water tubes one set above another and means for causing water to pass successively through the tubes 70 from set to set and downward until it reaches the bottom set, and means for automatically maintaining an independent water level in connection with the supply end of each set of tubes.

75

34. A water tube steam generator having substantially all of its steam generating water tubes inclined in the same direction and means for causing water to pass successively downward from tube to tube until it reaches 80 the bottom tubes, and means for automatically maintaining a predetermined water level in connection with the supply end of the lower tubes, said means being actuated responsive to variations in said water level 85 from a predetermined point.

35. A water tube steam generator having substantially all of its steam generating water tubes inclined in the same direction and means for causing water to pass successively 90 downward from tube to tube until it reaches the bottom tubes, and means for automatically maintaining a predetermined water level to flood the lower tubes, said means embracing a supply pipe, a steam and water 95 chamber, a steam pipe leading to said chamber from the water level in the bottom tubes, and a condenser for condensing steam in said chamber to cause the pressure without said chamber to raise the level of the water 100 therein so as to feed said supply pipe.

36. A water tube steam generator having its steam generating tubes arranged in series and means for automatically maintaining a predetermined water level to flood the 105 lower tubes, said means embracing a water supply chamber and means for raising the water level in said chamber by the condensation of steam and reduction of pressure.

37. A water tube steam generator having 110 its steam generating tubes arranged in banks and means for automatically maintaining a predetermined water level to flood the lower bank of tubes, said means embracing a supply pipe, a steam and water chamber, a steam pipe leading to said chamber from the water level in the bottom tubes, and a condenser for condensing steam in 115 said chamber to cause the pressure without said chamber to raise the level of the water 120 therein so as to feed said supply pipe.

38. In a steam generator a plurality of banks of water tubes, front and rear headers therefor, said tubes extending upwardly from one header to the other and lying in 125 substantially parallel planes whereby the space occupied by the tubes is reduced, and means for conducting the water from the

upper ends of each bank of tubes to the lower ends of the next succeeding bank of tubes below, and means for collecting steam from the headers at the upper ends of said tubes, and means for conducting away steam from the headers at lower ends of the tubes.

39. A steam generator composed of successive banks of straight water tubes, front and rear headers therefor, said tubes being all inclined in the same direction, all of said tubes receiving their supply of water at their lower ends and from the bank of tubes above after said water is freed from steam, and then discharging the steam generated in said bank of tubes from the upper ends into the upper part of the front headers, a steam drum and means for conducting the steam from the headers to the steam drum.

40. A steam generator composed of successive water tubes all inclined in the same direction, front and rear headers therefor, and means whereby all of the tubes receive their supply of water at their lower ends and from tubes above after said water has been freed from steam generated in the tubes above.

41. A steam generator composed of steam generating inclined water tubes arranged in banks and in which the steam generated always flows upwardly and with the water and substantially all the water flows downwardly from bank to bank whereby the water is progressively heated, and means for collecting the steam at the upper ends of the banks.

42. A steam baffle for steam generators comprising a hollow member closed at one end and open at the other and cut away on its top side.

43. A steam generator having a series of steam collecting headers, steam conducting pipes for connecting the front of each header with the front of the header below and baffles in front of the ends of said pipes, each baffle comprising a hollow member closed at its end farthest from said pipes, open at its end nearest said pipes, and a cutaway on its top side.

44. A water tube steam generator having substantially all of its steam generating water tubes inclined in the same direction and means for causing water to pass successively downward through said tubes until it reaches the bottom tubes, and means for automatically maintaining a predetermined water level to flood the lower tubes, said means embracing a water drum, a supply pipe, a steam and water chamber open at its bottom and extending nearly to the bottom of the water drum, a steam pipe leading to said chamber from the water level in the bottom tubes, a perforated plate in said pipe to restrict the passage of steam therethrough, and a condenser for condensing steam in said chamber to cause the pressure

without said chamber to raise the level of the water therein so as to feed said supply pipe.

45. A steam generator comprising a series of water tubes connected to form a series of loops in series with one another whereby the supply water will be fed progressively downward through said loops, each loop having two legs both extending downwardly from their point of connection and means for collecting the steam generated from the upper end of each loop.

46. A water tube steam generator having substantially inclined generating water tubes, means for causing water to pass successively downward through said tubes until it reaches the bottom tube, and means for automatically maintaining a predetermined water level to flood the lower tubes, said means embracing a water drum, a supply pipe, a steam and water chamber open at its bottom and extending nearly to the bottom of the water drum, a steam pipe leading to said chamber from the water level in the bottom tubes, means adapted to restrict the passage of steam therethrough, and a condenser for condensing steam in said chamber to cause the pressure without said chamber to raise the level of the water there- in so as to feed said supply pipe.

47. In a steam generator a plurality of sections of inclined generating tubes, a header for each end of each section, means for taking off steam from the headers at the upper end of each section, and means for conducting water from each of said last mentioned headers to the lower header of the next succeeding section.

48. The combination of a plurality of inclined steam generating water tubes, front and rear headers therefor, means for taking off steam from the upper header of each tube, and means for causing substantially all the water passing through a tube to pass to the lower header of a lower tube.

49. The combination of a plurality of inclined steam generating water tubes, means for taking off steam at the top end of each tube, and means for conducting substantially all of the water passing through a tube to the lower end of an adjacent tube, said conducting means being outside the main heat zone so that the generation of steam therein is substantially eliminated.

50. The combination of a plurality of inclined steam generating water tubes all inclined in the same general direction, means for taking off steam at the top end of each tube, and means for conducting substantially all of the water passing through a tube to the lower end of an adjacent tube, said conducting means being outside the main heat zone so that the generation of steam therein is substantially eliminated.

51. The combination of a plurality of in-

clined steam generating water tubes, means for taking off steam at the top end of each tube, and means for conducting substantially all of the water passing through a tube to the lower end of an adjacent tube.

52. The combination of a plurality of inclined steam generating tubes, means for causing substantially all water passing through a tube to pass to the lower end of a tube or tubes below, and means for taking off the steam from the upper ends of said tubes.

53. The combination of a plurality of banks of inclined steam generating water tubes, headers for both ends of said tubes, means for causing substantially all the water passing through one bank of tubes to pass to the lower end of the tubes of a bank below to supply the same, and means for taking off steam from the upper end of each bank.

54. A water tube steam generator having all its steam generating tubes inclined and fed with water at their lower ends whereby the water passes upwardly in said tubes with the steam generated, said tubes being arranged in banks and means passing at one side of said steam generating tubes for conducting water from the upper ends of one

bank of tubes to the lower end of an adjacent bank of tubes.

55. A water tube steam generator having all its steam generating tubes inclined and fed with water at their lower ends whereby the water passes upwardly in said tubes with the steam generated, and means for conducting water from the upper end of one tube to the lower end of an adjacent tube and so on, and means for taking off steam from the upper ends of each of said steam generating tubes.

56. In a steam generator a plurality of sections of inclined generating tubes all inclined in the same direction, a header for each end of each section, means for taking off steam from the headers at the upper end of each section, and means for conducting water from each of said last mentioned headers to the lower header of the next succeeding section.

In testimony whereof, I have signed my name to this specification, in the presence of two subscribing witnesses.

ALBERT A. CARY.
